US00D840220S

(12) United States Design Patent (10) Patent No.: US D840,220 S
 Bard et al. (45) Date of Patent:  Feb. 12, 2019

(54) PACKAGE

- (71) Applicant: Lutron Electronics Co., Inc.,
 Coopersburg, PA (US)
- (72) Inventors: Benjamin F. Bard, Zionsville, PA
 (US); David S. Bennett, Bethlehem, PA
 (US); Jason C. Killo, Emmaus, PA
 (US)
- (73) Assignee: Lutron Electronics Co., Inc.,
 Coopersburg, PA (US)
- () Term: 15 Years
- (21) Appl. No.: 29/622,233
- (22) Filed: Oct. 16, 2017

(57) CLAIM

The ornamental design for a package, as shown and described.

DESCRIPTION

FIG. 1 is a rear view of a package showing our new design; FIG. 2 is a left side view thereof; FIG. 3 is a right side view thereof; FIG. 4 is a bottom view thereof; and, FIG. 5 is a front view thereof.

The package is shown with a symbolic break in its length, width and height. The appearance of any portion of the article between the break lines forms no part of the claimed design.

1 Claim, 3 Drawing Sheets
